UNITED STATES PATENT OFFICE.

JOHN F. STANDISH, OF WINTHROP, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

FINISHING-MACHINE.

1,343,379.

Specification of Letters Patent. Patented June 15, 1920.

Application filed November 1, 1917. Serial No. 199,655.

To all whom it may concern:

Be it known that I, JOHN F. STANDISH, a citizen of the United States, residing at Winthrop, in the county of Suffolk and State of Massachusetts, have invented certain Improvements in Finishing-Machines, of which the following description, in connection with the accompanying drawings, is a specification, like reference characters on the drawings indicating like parts in the several figures.

My invention relates to machines for imparting a finish to the surfaces of such articles as shoes; it being more especially applicable to machines for burnishing the edges of shoe heels.

High heels of women's shoes which have a considerable pitch and curvature are usually inclined at the heel seat, being higher at the rear than at the breast. Such heels are difficult to burnish without rubbing and defacing the upper at the forward part of the heel, the rubbing members or burnishing tools tending to work over the upper at the same height from the rear to the breast. To operate rapidly upon such heels also gives trouble, since the tools heretofore employed have not been adapted to conform well to the long and varying curves. Moreover, in burnishing machines generally, the supply of wax or other finishing medium to the tools is not always satisfactory, the quantity delivered not being correct and lacking in uniformity.

This invention has for one of its objects the provision, in a finishing machine, of means whereby at such times as the rubbing members might come in contact with the upper, said members are so controlled that injury to the upper is prevented. This control I obtain through the movement of the work itself, by connecting, in the form of the invention illustrated, the work support to the burnishing members which are to be moved.

Another object of the invention is to furnish means for operating simultaneously and in an effective manner over the entire height of the heel. In attaining this result in accordance with one embodiment of the invention a series of rubbing members is provided, either with or without the work controlled series as the shape of the heel may

require, members of the first-mentioned series being adjustable in such a manner that it will generally conform in contour to the heel, and further making the members yieldable whereby they will conform exactly to the heel operated upon. As to attain a relatively perfect continuity of rubbing surface the individual members must be narrow in the direction of the height of the heel, I cause complete contact over the surface under treatment by moving members over at least a portion of the same area as those adjacent to them, so that no untreated surface is left. More specifically, adjacent rubbing members overlap one another, lying at an angle to the direction of movement.

A further object of the invention is to effect the application of wax or other finishing medium to the rubbing members in the proper quantity and regularly between the operations upon the work. To this end there is preferably interposed between the wax receptacle and rubbing members a plurality of members, one of which transfers a layer or film of the material upon a suitable surface from the receptacle to a point at which another member having an applying surface is brought into contact with such layer and then into contact with the rubbing members. The regular actuation of this feed may be governed by the work, there being shown herein connections between the work support and the driving mechanism for the applying means.

One organization for the accomplishment of this and other objects is herein described and illustrated in the accompanying drawings, in which—

Figure 1 is a top plan view of one form of my improved machine;

Fig. 2 is a side elevation, looking from the left in Fig. 1, the base portion of the frame being omitted;

Fig. 3 is a partial side elevation, taken from the same point as Fig. 2, illustrating another position of the elements, parts being broken away;

Fig. 4 is a partial top plan view with the wax receptacle removed;

Fig. 5 is a sectional detail on the line 5—5 of Fig. 4 showing one of the rubbing members and its supporting and actuating means;

Fig. 6 is a perspective view of the carrying and actuating means for the rubbing members, one of the work-controlled series of members being shown as separated from the adjacent carriers;

Fig. 7 is a perspective view of a portion of the actuating shaft and a carrier engaged thereby, and

Fig. 8 is a sectional detail of the controlling means for the wax-applying mechanism.

Journaled in a frame 10 is a shaft 12 for actuating the members which operate upon the work. This shaft is rocked in its bearings by a crank 14 joined by a connecting rod 16 to a crank 18 secured to a shaft 20 turning in the frame at the rear of the shaft 12. The shaft 20 also has fast upon it a crank 22 from which a connecting rod 24 extends to a crank disk 26 carried by the end of a main driving shaft 28. Friction connections 30 may be interposed between the disk 26 and the shaft 28, these being capable of slipping if undue strain is brought upon the machine in its operation.

At the outer extremity of the shaft 12, situated beyond a vertical wall 32 of the frame, is a square portion 34 at the inner side of which is an annular flange 36 adjacent to the wall 32 and shown as integral with the shaft. Upon this portion 34 are mounted carriers for a series of oscillatory rubbing or burnishing members which are to act over the greater portion of the work, considering, for example, in this connection the height of a shoe heel. These carriers, as shown, are in the form of generally rectangular frames 38 having elongated openings to fit the portion 34 to slide thereon, the openings being of sufficient length to permit this movement. Each carrier may be adjusted upon the portion 34 with respect to the work support, which will later be described, and fixed in position by a screw 40 threaded through the inner end of the carrier frame and having at its inner extremity a head 42 entering a T-slot in the portion 34. The screws may be turned by squared heads accessible through openings 44 in the frame to effect the desired independent adjustments. At the opposite end of each carrier from the screw 40 is an outwardly projecting portion 45 at the upper side of which is a pin 46. This pin enters a recess 50 in a rubbing or burnishing member, which includes a supporting portion 48 fitting the extension 45 of the carrier to slide thereon. A spring 52, seated in a cylindrical bore in the end of the extension 45, contacts with the opposite surface of the supporting portion 48, tending to force it outwardly until stopped by the contact of the pin 46 with the wall of the slot. Preferably integral with the portion 48 is the burnishing member proper, designated by the numeral 54,

65 having a working surface extending in the

shape of an arc through about 180° and being curved transversely, the sides of the adjacent members operating in contact with one another and being thus held against lateral movement. This working surface is 70 inclined at an angle to the supporting portion and to the direction of rubbing movement so that it overlaps the adjacent members, operating over the same areas. By this arrangement complete contact of the 75 burnishing tool as a whole with the work is assured. In addition to the burnishing members adjustable by the screws 40 upon the squared portion 34, this series includes an inner non-adjustable though yieldable 80 member mounted upon an extension 55 from the flange 36. This extension is similar to those numbered 45 and the manner of mounting the burnishing member on it is the same.

The purpose of the series of burnishing 85 members just described is to operate over that portion of the height of the heel from the top lift to the juncture of the breast and shank of the shoe. To coöperate with the remaining portion of the heel, which by the 90 inclination of the heel seat would tend to cause the rubbing members to come into contact with the upper adjacent to the breast of the heel, a second series of rubbing members is provided less in number than the first 95 series. These, in addition to their yield, are arranged to be oscillated by the actuating shaft 12 and also to be positively and automatically moved toward and from the work. For this purpose each member is mounted 100 upon a compound carrier consisting of a slide or primary member 56 guided between a bed plate 58 upon the frame and an upper plate 60. An outer member 59 held by bolts 61 passing through slots 63 in the plates 58 105 and 60 retains the members 56 in place and allows their number to be varied. At the outer end of each member 56 is a recess having an arcuate wall 62 extending through more than 180°. The secondary member 64 110 of the carrier has a circular portion fitting within the recess and retained by the forward ends of the wall 62 and also has an extension 66, the latter carrying the burnishing member proper, which may be in all respects similar to the members 54 previously described. To connect the outer or automatically adjusted series of members, so that they may be oscillated by the rock-shaft 12, this shaft has an axial opening 115 through which extends a rod 68 secured in place by a nut 70 threaded upon the outer end. This serves to draw a head 72 upon the opposite end of the rod against the squared portion 34 of the shaft to retain the 120 carriers 38 in place thereon, a reduced portion 73 of the head entering the opening in the preceding carrier. The head 72 serves as an intermediate carrier, this being non-adjustable but bearing upon it one of the 130

burnishing members 54 pressed outwardly by a spring 52. A slot 75 in the outer face of the member 72 receives a connecting member or key 74 in the shape of a cross having two members lying side by side in different planes at right angles to one another. The length of the member entering the slot in the carrier 72 is such that it may be slid therein. The other member of the key fits a vertical slot 76 in the first of the secondary carrier members 64. This connection permits this first carrier of the second series with its burnishing member to be moved longitudinally while it receives an oscillatory movement from the shaft 12. There may be in this second series as many as are necessary to cover the inclined upper portion of the heel, they being joined for the longitudinal and oscillatory movement by other keys 74. The alternate members 64 have horizontal slots, instead of the vertical slot 76 as in the device just described, which are sufficient in length to permit the horizontal travel of the carrier. In the present instance three carriers and burnishing members are shown in the second series.

To actuate the carriers 56 with their burnishing members to obtain positive movement at such predetermined times as the form of the heel to be burnished may require, each of the carrier members 56 has a rounded extremity 78 contacting with one of a set of cams 80. The cams are fixed against a shoulder upon the end of a shaft 82, journaled in a bracket in the rear of the frame, by means of a nut 84 threaded upon the end of the shaft. By the removal of this nut the proper number of cams may be applied to the shaft, and when the nut is put on and tightened, it will retain the cams at the angles in which they are positioned. The carriers are forced against the cams by coiled springs 86, the outer hooked ends 88 of which engage recesses in the carrier portions 56, while their inner extremities are secured to a shaft 90 mounted to turn at the bottom of the frame. This shaft has fixed upon it a ratchet wheel 92 and a handle 93, the ratchet wheel having co-operating with it a pawl 94 pivoted upon the frame. This pawl retains the shaft 90 in the position to which it may be turned by the handle, enabling the tension of the springs and the force with which the carriers are pressed against the cams to be varied. Each cam has rising from its cylindrical surface a projection 96 of sufficient height to move the corresponding rubbing member into contact with the shoe heel at the proper time, the cylindrical surface allowing the withdrawal of the rubbing member when it would contact with the upper of the shoe.

To properly time the cams in their rotation, their operation is governed by the movement of the work itself during bur-

nishing. Fast upon the shaft 82 is a sprocket wheel 98 connected by a chain 100 to a sprocket wheel 102 secured to a shaft 104 rotatable in the frame at the front of the machine. The end of the shaft 104 adjacent to the rubbing members carries a universal joint 106 upon which is mounted a work support, here shown as consisting of a swinging bar 108 upon which is mounted to slide a loop 110 drawn inward by a spiral spring 112. The toe of the shoe, the heel of which is to be burnished, is inserted in the loop 110, in which position the breast of the heel contacts with a fulcrum point or rest furnished by a roll 114 rotatable upon the forward extremity of a bar 116, the opposite end of which surrounds a stub shaft 118 projecting from the frame, being clamped thereon by a screw 120 extending through a divided portion of the bar. Adjustment of the bar upon the shaft 118 varies the distance between the fulcrum roll 114 and burnishing members so that heels of different diameter may be satisfactorily operated upon. In burnishing a heel, as the work support is swung about the axis of the shaft 104, the cams 80 are correspondingly rotated by the gearing to properly actuate the carriers 56.

At the top of the machine, to the rear of the burnishing members, is supported a tank or receptacle 122 for the material which is to be applied to the work, as wax for burnishing heels or some other finishing medium, this receptacle being heated, if desired, by any convenient means. Below the receptacle, near the bottom of the frame, is pivoted an arm 124 upon the wide upper angular end 128 of which is fulcrumed a lever consisting of two pivotally connected arms 126 and 127 extending respectively over the top of the tank 122 and downwardly at one side thereof. Contacting projections 129 on the arms limit their angular movement toward one another, while plungers 162 mounted in a series of bores in the portion 128 of the arm 124 are pressed by springs 164 against a cam surface 160 on the arm 126 to normally maintain the projections 129 in contact. This arrangement allows the arm 126 to be swung back manually upon its pivot, when desired, to clear the top of the tank. The arm 126, at the extremity toward the burnishing members, carries a yieldable applying member or pad 130 the surface of which is adapted to conform to the contour of the burnishing tool as a whole and to apply the contents of the receptacle over its entire width. The member 130 is moved from a point over the receptacle to a point over the burnishing members by a block 132 mounted to reciprocate in a slot 134 in the arm 124. The block is rotatably carried by a pin projecting from the side of a gear 136 which is free

to turn upon the frame. Meshing with the gear is a pinion 138 fast upon a shaft 140 journaled in the frame at its rear portion. Upon the shaft 140 is a clutch 142, illustrated as of the jaw type, one member turning loosely upon the shaft and having secured to it a pulley 144 which is constantly driven by a belt 146 from a belt surface 148 formed upon the crank disk 26. The cooperating clutch member is in two sections, one, 150, being secured to the shaft 140 by a set screw while the other section 152 has a sleeve surrounding the shaft which is connected to turn with the section 150 by a spiral spring 154. Movable on the clutch sleeve is a collar through which is threaded a screw 151, passing through an inclined slot 153 in the sleeve into a slot 155 in the shaft 140 and parallel to the axis thereof. The expansive force of this spring tends normally to force the jaws of the clutch into contact so that the shaft 140 may be rotated by the pulley 144, the engagement of the screw 151 with the slot 155 compelling clutch section 152 and the shaft to turn together.

To raise and lower the applying member 130 from the position to which it is moved by the arm 124 over the receptacle and over the burnishing members with respect to said receptacle and burnishing members, the arm 127 of the applying lever carries a roll 156 operating over a cam surface 158 carried at one side of the receptacle. As the lever 126-127 is oscillated between the receptacle and the burnishing members by the rotation of the gear 136 and the consequent rocking of the arm 124, the roll rides upon the cam surface, which is of such form that the lever is swung vertically upon the arm to raise and lower the applying member 130 at the proper times at its extreme points of movement by the arm.

To avoid carrying an excess of material upon the applying member 130 from the receptacle to the rubbing members, a transfer member is interposed between the applying member and receptacle. This, as illustrated, consists of a plate 166 which may be immersed in the contents of the receptacle and when raised carries upon its upper surface a suitable layer of the material to the applying member. I have shown the plate as in the form of a swinging shelf at the ends of which are lugs 168 pivoted upon the double parallel arms 170 of a lever 172 fulcrumed at one end of the receptacle. Beyond the fulcrum the lever has a single arm 173, upon the upper side of which is a cam surface 176 over which rubs a contact member 174 carried by the portion 128 of the arm 124. In the oscillation of the arm 124 the contact member moves over the cam surface 176, the latter being of such shape

that at the extreme of rearward movement 65 of the arm, when the applying member 130 is within the receptacle, the transfer plate 166 is raised from its position in the fluid into contact with the applying surface, it tipping upon its pivot to give perfect contact with said surface. As the applying member is moved forward toward the burnishing members, the form of the cam surface 176 permits the transfer member to again fall into the receptacle to receive another charge of the material.

It is desired to apply material in the receptacle to the burnishing members in some predetermined relation to the operation upon the work, as after a complete burnishing action upon a single shoe heel. To attain this, the clutch controlling the driving of the shaft 140, and therefore the operation of the supplying mechanism, is governed by the work support through the shaft 82 and connecting sprocket gearing. Upon the shaft 82 is a collar 178 fixed in place by a set screw and having a pin 180 movable in the rotation of the shaft to contact with a detent 182 pivoted upon a retaining member or latch 184. The opposite extremity of the latch swings upon a fixed arm 186, and in the under surface of the latch is a notch 188 which may be engaged by a projection 190 upon the section 152 of 95 the clutch. Normally, or when the work support is in its initial position as illustrated in Fig. 2 of the drawings, the jaws of the clutch are separated, being so retained against the tension of the spring 154 100 by the engagement of the projection 190 with the notch 188, and the pin 180 is just at the inner side of the detent 182. As the shaft 82 is rotated through the sprocket gearing by turning the work support in 105 burnishing the heel, the pin passes idly under the detent, the latter being so mounted as to permit it to yield. Upon the return movement of the work support, as the heel is being passed over the burnishing members 110 a second time, the pin strikes the detent, which now resists its passage, and rides under a curved surface 194 of the detent, causing the latch to be raised freeing the projection 190 from the notch. The spring 115 154 expanding moves the section 152 of the clutch longitudinally of the shaft 140 so that the jaws are brought into engagement, causing the shaft to be rotated by the action of the pulley 144. This continues through 120 a complete rotation of the shaft and one cycle of movement of the wax-applying mechanism, at the end of which time the projection 190 again engages the notch 188. In the continued rotation of the collar and 125 shaft after the sleeve has been stopped by this engagement the screw 151 travels in the inclined slot 153, thus sliding the collar to

the left, as seen in Fig. 1 of the drawings, and separating the jaws. This stops the action of the wax-applying mechanism.

The operator in using the machine adjusts the inner series of rubbing members by means of the screws 40 until the contour of this portion of the burnishing tool generally corresponds to that of the heel to be operated upon, except for the portion adjacent to the upper. Here the proper number of the outer series of rubbing members is put in place and cams 80 of the correct outline are positioned upon their shaft to withdraw the rubbing members which they control from the work at such times as they might contact with the upper of the shoe. The toe of the shoe the heel of which is to be burnished is then inserted in the loop 110 of the work support, the breast of the heel resting upon the roll 114. In the vertical position of the work support, illustrated in Fig. 2, one of the forward edges of the heel may be brought into contact with the burnishing members which, as they are oscillated by the shaft 12, operate over the entire height of the heel, they yielding to compensate for any imperfections of adjustment or inequalities in form. As the work support is rotated, the cams are correspondingly moved and the outer series of rubbing members, which are first held out of contact with the shoe to avoid injury to the upper, are allowed to come into contact with the heel, this occurring when the work support is approximately in a horizontal position. As it rises, the cams again separate the outer series of members from the work. After having operated over the surface of the heel in one direction, the movement of the support is reversed for a second operation to complete the burnishing, the cams again controlling the positions of the outer series of rubbing members. When the work support approaches its lowest point, the clutch retaining member 184 is tripped by the contact of the pin 180 with the detent 182. Thus, after a complete burnishing operation, the wax-applying mechanism is thrown into action, and the applying member 130, having taken its charge of wax from the transfer member 166, is moved forward by the arm 124 until it contacts with the rubbing faces near their upper extremities. The oscillation of these faces distributes the wax over the entire working length in preparation for burnishing the succeeding heel and the member 130 is returned to its position above the receptacle to receive the succeeding charge. When the applying member 130 strikes either the transfer member or the burnishing members, the arm 126 may yield upwardly against the tension of the springs 161. This insures firm contact in both instances.

Having thus described my invention, what

I claim as new and desire to secure by Letters Patent of the United States is:—

1. In a heel finishing machine, a series of work-rubbing members, the work and the rubbing members traveling relatively to one another to present successive portions of the work to the rubbing action, and means for producing a relative movement of separation between part of the rubbing members and the work during the travel whereby said part of the members are wholly prevented from acting on predetermined portions of said work opposite which they are situated. 65 70 75

2. In a machine of the class described, an oscillatory work-rubbing member, means for guiding the work over the member, and means for separating the member and work during a portion of the travel of the work. 80

3. In a machine of the class described, a work-rubbing member, and means governed by the movement of the work in a plurality of directions for moving said member out of contact with the work. 85

4. In a machine of the class described, a plurality of work-rubbing members, and means governed by the movement of the work in opposite directions over the rubbing members for varying the position of said members with respect to the work. 90

5. In a heel-burnishing machine, a plurality of movable burnishing members for operating upon the heel, and means governed by the position of the heel for moving a burnishing member into and out of contact with said heel whereby an irregularly shaped heel may be burnished without injury to the upper by the burnishing member. 95 100

6. In a machine of the class described, a plurality of work-rubbing members operating side by side upon adjacent portions of the work, and means for differently varying the position of said members with respect to the work. 105

7. In a machine of the class described, a work-rubbing member, and means governed by the work for moving said member out of contact with said work during a portion of the operation. 110

8. In a machine of the class described, a plurality of rubbing members operating side by side over successive portions of the work, and means for producing a relative movement between certain of the members and the work whereby they are separated. 115

9. In a machine of the class described, an oscillatory work-rubbing member, means for guiding the work over the member, and means including a cam for varying the position of said member toward and from the work. 120 125

10. In a machine of the class described, work-rubbing members operating adjacent to one another, and means acting upon plu-

- ral members for differently varying their distance from the work.
11. In a machine of the class described, a work-rubbing member, means for moving the member, a work support, and connections between the work support and rubbing member controlling the movement of the member.
12. In a machine of the class described, a work-rubbing member, means for moving the member, a rotatable work support, and means turning with the support for governing the moving means.
13. In a machine of the class described, a work-rubbing member, means for moving the member, a rotatable work support, and sprocket gearing connecting the support and moving means.
14. In a burnishing machine, a reciprocating carrier, a burnishing tool mounted upon the carrier, means for oscillating the tool, and means operating upon the carrier to move the tool toward and from the work.
15. In a burnishing machine, a slideable carrier, a burnishing tool mounted to turn upon the carrier, a cam coöperating with the carrier, and a rock-shaft coöperating with the tool.
16. In a machine of the class described, a series of closely adjacent work-rubbing members, means for mounting a portion of the members to yield with respect to the work, and means for moving another portion of the members toward and from the work.
17. In a machine of the class described, a plurality of work-rubbing members, means for mounting a greater portion of the members to yield to conform to the contour of the work, and means for moving other members toward and from the work.
18. In a machine of the class described, a plurality of work-rubbing members alined in a direction transverse to their rubbing action, means for mounting a portion of the members to yield with respect to the work, and means for moving another portion of the members out of contact with the work during a portion of the operation.
19. In a heel-burnishing machine, a plurality of movable burnishing members for operating upon the heel, means for determining the position of a portion of the members to conform to the contour of the heel, and means controlled by the position of the heel for moving another portion of the members into and out of contact with said heel whereby an irregularly shaped heel may be burnished without injuring the upper.
20. In a heel-burnishing machine, a plurality of movable burnishing members, and means constructed and arranged to move said members whereby they may be caused to conform generally to the contour of the heel to be burnished.
21. In a machine of the class described, oscillatory actuating means, a plurality of carriers coöperating with the actuating means, and rubbing members mounted upon the carriers and being movable with respect to the actuating means.
22. In a machine of the class described, oscillatory actuating means, a plurality of carriers coöperating with the actuating means, rubbing members mounted upon the carriers, and means constructed and arranged to fix the carriers in different positions upon the actuating means.
23. In a machine of the class described, oscillatory actuating means, a plurality of carriers coöperating with the actuating means, and rubbing members yieldably mounted upon the carriers.
24. In a machine of the class described, oscillatory actuating means, a plurality of carriers coöperating with the actuating means, rubbing members yieldably mounted upon the carriers, and means constructed and arranged to fix the carriers in different positions on the actuating means.
25. In a burnishing machine, a rock-shaft, a carrier mounted to slide on the rock-shaft, and a burnishing member mounted upon the carrier.
26. In a burnishing machine, a rock-shaft, a carrier mounted to slide on the rock-shaft, a screw threaded through the carrier and engaging the rock-shaft, and a burnishing member mounted upon the carrier.
27. In a burnishing machine, a rock-shaft, a carrier mounted to slide on the rock-shaft, a burnishing member movable upon the carrier, and a spring interposed between the carrier and burnishing member.
28. In a burnishing machine, a rock-shaft, a carrier mounted to slide on the rock-shaft, a screw threaded through the carrier and engaging the rock-shaft, a burnishing member movable upon the carrier, and a spring interposed between the carrier and burnishing member.
29. In a burnishing machine, an actuating member, a plurality of rubbing members mounted upon the actuating member and being provided with slots, and connecting members common to adjacent rubbing members and coöperating with the slots.
30. In a burnishing machine, an actuating member, a plurality of rubbing members mounted upon the actuating member and being provided with slots extending in different directions, and a key having angular portions entering the slots.
31. In a burnishing machine, a rock-shaft including a sleeve and a shaft within said sleeve, both sleeve and shaft having squared portions, and burnishing means mounted upon the squared portions.
32. In a machine of the class described, a frame, a series of rubbing members mov-

able upon the frame, and a retaining member for the rubbing members, said retaining member being variable in position to allow the number of rubbing members in the series 5 to be varied.

33. In a machine of the class described, a frame, a series of rubbing members movable upon the frame, a fixed abutment for the members at one end of the series, and 10 movable retaining means contacting with the member at the other end of the series.

34. In a machine of the class described, a frame including opposite plates having slots, a series of rubbing members movable 15 between the plates, a retaining member engaging a rubbing member, and bolts extending through the slots and contacting with the retaining member.

35. In a machine of the class described, 20 a plurality of rubbing members situated in proximity to one another, and means for oscillating the members to effect their rubbing action, each of said members in its oscillation operating over the same area as 25 those adjacent to it.

36. In a machine of the class described, a series of work-engaging members movable in contact with one another in their operation upon the work but held by such contact against lateral movement, said members having extended rubbing faces lying at 30 an angle to the direction of operating movement.

37. In a machine of the class described, 35 work-engaging members having extended rubbing faces, and means for oscillating the members to effect their rubbing action, said members overlapping one another in the direction of oscillation.

38. In a machine of the class described, a 40 plurality of rubbing members having parallel supporting portions and work-engaging portions lying at an angle to the supporting portions, and means for moving the 45 members together about the supporting portions.

39. In a machine of the class described, a member for operating upon the work, a material receptacle, means for intermittently 50 applying the material to the member, and means for transferring the material from the receptacle to the applying means.

40. In a shoe-finishing machine, a finishing member, a receptacle for a finishing medium, an applying member movable from a 55 point in proximity to the receptacle to the finishing member, and a transfer member movable from within the receptacle into contact with the applying member.

41. In a shoe-finishing machine, a finishing member, a receptacle for a finishing medium, and a plurality of oscillatory members 60 cooperating to deliver the finishing medium from the receptacle to the finishing member.

42. In a shoe-finishing machine, a finishing member, a receptacle for a finishing medium, a plurality of oscillatory members coöperating to deliver the finishing medium from the receptacle to the finishing member, 70 and relatively fixed means for oscillating one of the members.

43. In a shoe-finishing machine, a finishing member, a receptacle for a finishing medium, a plurality of oscillatory members 75 coöperating to deliver the finishing medium from the receptacle to the finishing member, and relatively fixed means for oscillating one of the members, said members coöperating to effect the oscillation of another member. 80

44. In a shoe-finishing machine, a finishing member, a receptacle for a finishing medium, a transfer member, means for immersing the transfer member in the finishing medium and withdrawing it therefrom, and a member movable alternately into contact with the transfer member and with the finishing member. 85

45. In a shoe-finishing machine, a plurality of finishing members, a receptacle for a finishing medium, flexible means for intermittently applying the medium to the members, and means for transferring the medium from the receptacle to the applying 90 means. 95

46. In a shoe-finishing machine, a finishing member, a receptacle for a finishing medium, movable means for intermittently applying the medium to the member, and 100 movable means for transferring the medium from the receptacle to the applying means, one of said means effecting the movement of the other.

47. In a shoe-finishing machine, a finishing member, a receptacle for a finishing medium, means for intermittently applying the medium to the member, and means actuated by the applying means for transferring the medium from the receptacle to the applying 105 means. 110

48. In a shoe-finishing machine, a finishing member, a receptacle for a finishing medium, means for intermittently applying the medium to the member, and means movable into and out of the medium and contacting with the applying means to transfer the medium thereto when the movable means is out of said medium. 115

49. In a burnishing machine, the combination with a burnishing member and a wax receptacle, of an oscillatory arm, a lever fulcrumed upon the arm and provided with a wax-applying surface, and means for oscillating the arm and rocking the lever thereon 120 to move the wax-applying surface into cooperation with both the receptacle and member. 125

50. In a burnishing machine, the combination with a burnishing member and a wax 130

- receptacle, of an oscillatory arm, a lever fulcrumed upon the arm and provided with a wax-applying surface, means for oscillating the arm to move the wax-applying surface between points over the receptacle and over the burnishing member, and means for rocking the lever upon the arm to move the wax-applying member toward and from the receptacle and member.
51. In a burnishing machine, the combination with a burnishing member and a wax receptacle, of an oscillatory arm, a lever fulcrumed upon the arm and provided with a wax-applying surface, means for oscillating the arm, a lever having a wax-transferring surface, and means for moving the transferring surface into the wax and into co-operation with the applying surface.
52. In a burnishing machine, the combination with a burnishing member and a wax receptacle, of an oscillatory arm, a lever fulcrumed upon the arm and provided with a wax-applying surface, means for oscillating the arm, a lever having a wax-transferring surface, and means carried by the arm for moving the transferring surface into the wax and into co-operation with the applying surface.
53. In a burnishing machine, the combination with a burnishing member and a wax receptacle, of an oscillatory arm, a lever fulcrumed upon the arm and provided with a wax-applying surface, means for oscillating the arm to move the wax-applying surface between points over the receptacle and over the burnishing member, and a cam for rocking the lever upon the arm to move the wax-applying member toward and from the receptacle and member.
54. In a shoe-finishing machine, a finishing member, a receptacle for a finishing medium, an arm provided with an applying surface movable between the receptacle and finishing member, and a mounting for said arm permitting it to yield upon contact of its applying surface.
55. In a shoe-finishing machine, a finishing member, a receptacle for a finishing medium, a lever having two arms, one of which is provided with an applying surface movable between the receptacle and finishing member, and a connection between the arms permitting the applying arm to be swung clear of the receptacle independently of the associated arm.
56. In a shoe-finishing machine, a finishing member, a receptacle for a finishing medium, a lever having an arm provided with an applying surface and also having an actuating arm, means coöoperating with the actuating arm for moving the lever, and yieldable connections between the arms.
57. In a shoe-finishing machine, a finishing member, a receptacle for a finishing me-

dium, an oscillatory member, and a lever carried by the member and comprising arms pivoted to one another, one of said arms being provided with an applying member coöoperating with the receptacle and the finishing member in the movement of the oscillatory member.

58. In a shoe-finishing machine, a finishing member, a receptacle for a finishing medium, an oscillatory member, a lever carried by the member and comprising arms pivoted to one another, one of said arms being provided with an applying member coöoperating with the receptacle and finishing member in the movement of the oscillatory member, and a spring carried by the oscillatory member and acting to hold the lever arms in a normal relation to one another.

59. In a machine of the class described, means for operating upon the work, means for supplying material to the operating means, and means controlled by the position of the work to govern the action of the supplying means.

60. In a finishing machine, means for operating upon the work, means for supplying a finishing medium to the operating means, and means operating subsequently to a complete application of the work to the operating means for governing the action of the supplying means.

61. In a machine of the class described, means for operating upon the work, movable means for supplying material to the operating means, means for controlling the movement of the supplying means, a movable work support, and connections between the work support and controlling means.

62. In a machine of the class described, means for operating upon the work, movable means for supplying material to the operating means, means for controlling the movement of the supplying means, a movable work support, and connections between the work support and controlling means, said connections being constructed and arranged to affect the controlling means after a predetermined movement of the work support.

63. A machine for burnishing the heels of shoes, comprising a burnishing member, traveling wax-applying means, a shoe support, means for controlling the travel of the applying means, and connections between the support and controlling means constructed and arranged to actuate the controlling means after the surface of the heel to be burnished has been presented to the burnishing member.

64. In a machine of the class described, work-rubbing members, a receptacle, mechanism for transferring material from the receptacle to the rubbing members, driving means, shiftable connections between the driving means and the transferring mecha-

nism, a work support, and means governed by the work support for shifting the connections.

65. In a machine of the class described, 5 work-rubbing members, a receptacle, mechanism for transferring material from the receptacle to the rubbing members, driving means, shiftable connections between the driving means and the transferring mechanism, 10 a work support, and means governed by the work support for shifting the connections to effect the engagement of the connections to actuate the mechanism, said connections being provided with means for 15 causing their disengagement upon a predetermined movement of the mechanism.

66. In a machine of the class described, 20 work-rubbing members, a receptacle, mechanism for transferring material from the receptacle to the rubbing members, driving means, a clutch between the driving means and the transferring mechanism, a retaining member for the clutch, a movable work support, and means operable from the work 25 support to actuate the retaining member.

67. In a machine of the class described, 30 work-rubbing members, a receptacle, mechanism for transferring material from the receptacle to the rubbing members, driving means, a clutch between the driving means and the transferring mechanism, a spring tending to hold sections of the clutch in co-operation, a latch engaged by one of the clutch sections under the tension of the 35 spring, a work support, and means controlled by the work support for releasing the clutch from the latch.

68. In a machine of the class described, 40 work-rubbing members, a receptacle, mechanism for transferring material from the receptacle to the rubbing members, driving means, a clutch between the driving means and the transferring mechanism, a spring tending to hold sections of the clutch in co-operation, a latch engaged by one of the clutch sections under the tension of the 45 spring, a work support, and means controlled by the work support for temporarily releasing the clutch from the latch to permit the engagement of the sections, the latch thereafter co-operating with the clutch to 50 disengage the sections.

69. In a machine of the class described,

a rubbing member, means for controlling the position of the member, means for applying material to the member, and means common to both for governing the controlling means and the applying means. 55

70. In a machine of the class described, 60 a rubbing member, means for controlling the position of the member, means for applying material to the member, and movable means common to both for governing the controlling means and the applying means, said common means requiring a different 65 number of movements to operatively affect the controlling means and applying means.

71. In a machine of the class described, 70 a rubbing member, means for controlling the position of the member, means for applying material to the member, and movable means common to both for governing the controlling means and the applying means, said common means operatively affecting the controlling means in each movement and 75 the applying means only upon a plurality of movements.

72. In a machine of the class described, 80 a rubbing member, means for controlling the position of the member, means for applying material to the member, driving mechanism therefor, a work support, a shaft connected to the work support, and means carried by the shaft for controlling the rubbing member and the driving mechanism. 85

73. In a machine of the class described, 90 a rubbing member, means for controlling the position of the member, means for applying material to the member, driving mechanism therefor, a retaining member for the driving mechanism, a shaft connected to the work support, a cam fixed to the shaft and co-operating with the rubbing member, and a member movable with the shaft and contacting with the retaining member. 95

74. In a heel-burnishing machine, a plurality of movable burnishing members for operating upon the heel, and means governed by the position of the heel for controlling the operation of the burnishing 100 members in such a manner that a heel may be burnished without injury to the upper.

In testimony whereof I have signed my name to this specification.

JOHN F. STANDISH.
